Primary Examiner — David Muller*Assistant Examiner* — Nathan Johnston(74) *Attorney, Agent, or Firm* — Global IP Services; Tianhua Gu(57) **CLAIM**

The ornamental design for a massage armchair, as shown and described.

DESCRIPTION

FIG. 1 is a front elevation view of a massage armchair showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a front perspective view thereof; and,

FIG. 7 is a rear perspective view thereof.

The broken lines depict portions of the massage armchair that form no part of the claimed design.
